UNITED STATES PATENT OFFICE.

CHARLES L. PEIRCE, JR., OF CHICAGO, ILLINOIS, ASSIGNOR TO PEIRCE SPECIALTY COMPANY, OF CHICAGO, ILLINOIS, A CORPORATION OF ILLINOIS.

CONNECTOR FOR TELEPHONE AND OTHER WIRES.

No. 832,876.

Specification of Letters Patent.

Patented Oct. 9, 1906.

Application filed May 31, 1905. Serial No. 263,145.

To all whom it may concern:

Be it known that I, CHARLES L. PEIRCE, Jr., a citizen of the United States, residing at Chicago, in the county of Cook and State of Illinois, have invented certain new and useful Improvements in Connectors for Telephone and other Wires, of which the following is a specification.

My invention relates to connecting devices for the wires of telephone, telegraph, and other circuit-lines, and has for its principal object to provide a simple, economical, and easily-manipulated connector or clamp, more especially designed for joining main and branch circuit line-wires of telephone systems, although capable of use where meeting line-wires of any electric circuit are to be electrically united.

My invention in a simple and preferred form is illustrated in the accompanying drawings, wherein—

Figure 1 is an end elevational view of the device as it appears in operative position. Fig. 2 is a side elevational view of the same. Figs. 3 and 4 are detail views of opposite sides of the principal body member of the clamp. Fig. 5 is an end elevational view of the latter. Fig. 6 is a detail elevational view of the clamping-bolt. Fig. 7 is a side elevational view, detached, of the intermediate conductor-plate; and Fig. 8 is a plan view of a blank from which the body member of the clamp is bent up.

Referring to the drawings, 10 and 11 may designate a pair of line-circuit telephone or other wires which are to be electrically connected by the device of my invention. For the purpose of illustrating the chief intended application of the device 10 may be assumed to be a main-line telephone-wire and 11 a branch line-wire leading off to a subscriber's station on the main line, which wires are to be connected so as to be in electrical communication by the device of my invention.

12 designates the principal body member of the connecting device which may be conveniently and cheaply formed from a blank of elastic sheet metal, preferably brass, such as shown in Fig. 8, said blank being suitably punched or stamped to provide a pair of holes 13, which when the device is bent into the U shape illustrated in Figs. 1 and 5 register with each other to receive a clamping-bolt 14.

said blank being further apertured at its center, as shown by the hole 15, for a purpose 55 hereinafter described. 16 designates a conductor-plate, preferably of copper, said plate being of substantially the width of the body 12 at one end and at its opposite end tapering to a point 16^a. This plate is also provided 60 with a substantially central hole 17. The fastening-bolt 14 has a head 14^a and between the inner flat face of the latter and the stem or shank of the bolt is provided with a web 14^b, adapted, when the device is connected 65 up, to engage a notch 13^a, formed in the margin of one of the holes 13, to thereby prevent the bolt from turning when the clamping-nut 18 and lock-nut 19 are applied thereto.

It will be observed that the upper opposite 70 end portions of the U-shaped body 12 are transversely crimped or bent to provide a pair of seats 12^a and 12^b for the wires 10 and 11, respectively.

In applying the connector the parts are 75 assembled in the manner plainly indicated in Figs. 1 and 2, the plate 16 lying between the sides of the body 12, with its point or tongue 16^a engaged with the hole 15, which forms a seat therefor to prevent either lateral 80 or edgewise displacement of the plate, and the clamping-bolt 14 passed through the registering apertures of said body and plate. The adjacent ends of the wires to be connected are passed through the upper portion 85 of the body 12, one on either side of the intermediate conducting-plate, said wires on turning up the nuts 18 and 19 being very rigidly and securely clamped in the grooves or seats 12^a and 12^b and pressed hard against 90 the intervening copper conductor-plate, thereby establishing ample electrical conduction between said wires across or through said conductor-plate. The sides of the U-shaped body being resilient and tending to spring 95 apart forces the threads of the nuts 18 and 19 hard into frictional engagement with the cooperating thread of the bolt, thereby preventing any tendency of said nuts to work loose and back off the bolt. The engagement of the tip or point of the conductor-plate 16 with the hole 15 in the bend of the body maintains said conductor-plate in true central relation to the sides of the body and the conducting-wires connected thereby, the 100 bolt 14 at the same time securely locking said 105

conductor-plate against displacement. To remove the connector, it is necessary only to take the nuts 18 and 19 off the bolt and separate the sides of the body 12 sufficiently to withdraw the wires 10 and 11.

Not being permanently secured to either of the wires 10 or 11 in the event that either of said wires is destroyed or discarded, the clamp is readily applicable to a new or substituted wire. Aside from its use to connect main and branch wires of telephone and other circuits it may conveniently be used to connect in fuses and in many other relations where a simple connecting device is required between two wires which are to constitute a continuous conductor for an electric current.

I do not limit the invention to the specific construction therefor herein shown and described, as it is evident that the details and forms of the several parts might be considerably modified without departing from the spirit or lessening any of the benefits of the invention.

25 I claim—

1. A connector for telephone and other wires comprising a clamping member having substantially parallel sides, a plate of conducting material inserted between the sides 30 of said clamping member, and means for drawing the sides of said clamping member together upon the wires whereby to clamp the latter against the opposite sides of said conducting-plate, substantially as described.

35 2. A connector for telephone and other wires comprising a generally U-shaped clamp

having seats for the wires to be connected formed in its inner opposed faces, a conductor-plate carried by said clamp and adapted to lie between said wires, and means for drawing the sides of said clamp toward said conductor-plate whereby to clamp the wires upon the latter, substantially as described.

3. A connector for telephone and other wires comprising a generally U-shaped elastic 45 clamp having parallel transverse seats for the wires to be connected formed in its inner opposed faces, a conductor-plate carried by said clamp, and adapted to lie between said wires, and means for drawing the 50 sides of said clamp toward said conductor-plate, whereby to clamp the wires upon the latter, substantially as described.

4. A connector for telephone and other wires comprising a generally U-shaped elastic 55 clamp having seats for the wires to be connected formed in its inner opposed faces and further having a pair of registering holes formed through its sides and a seat formed in its closed end, a conductor-plate carried 60 by said clamp, and adapted to lie between said wires, said conductor-plate having an aperture in line with the apertures of said clamp and a point or tongue fitting said seat, and a bolt and nut whereby to draw together 65 said clamp and conductor-plate upon the wires, substantially as described.

CHARLES L. PEIRCE, JR.
